(57) **CLAIM**

The ornamental design for a two stones jewelry piece, as shown and described.

DESCRIPTION

FIG. 1 is a perspective view of the two stone jewelry piece showing my new design;

FIG. 2 is a top view thereof;

FIG. 3 is a front view thereof;

FIG. 4 is a side view thereof;

FIG. 5 is a perspective view of a second embodiment of my new design, the earring loop shown in dotted lines for illustrative purposes only and form no part of the claimed design;

FIG. 6 is a top view thereof;

FIG. 7 is a front view thereof;

FIG. 8 is a side view thereof;

FIG. 9 is a front view of a third embodiment of my new design, the part of a necklace shown in dotted lines for illustrative purposes only and form no part of the claimed design;

FIG. 10 is a top plan view thereof;

FIG. 11 is a front view thereof; and,

FIG. 12 is a side view thereof.
